UNITED STATES PATENT OFFICE.

SIMEON S. JACKSON, OF HYDE PARK, MASSACHUSETTS, ASSIGNOR TO THE STAFFORD COMPANY, OF BOSTON, MASSACHUSETTS, A CORPORATION OF MASSACHUSETTS.

WEFT-REPLENISHING LOOM.

Application filed July 31, 1925. Serial No. 47,259.

The invention is designed for application to automatic weft-replenishing looms, and in particular to such looms of this class as operate to effect weft-replenishment prior to complete exhaustion of the shuttle-contained weft-supply. Such looms are equipped with means for parting the old weft-thread at the mouth of the shuttle-box at that side of the loom at which replenishment is effected, just prior to the expelling of the substantially depleted weft-carrier from the shuttle to make way for the fresh supply of weft. This parting of the weft-thread is necessary in order to allow the old weft-end to be drawn out of the eye of the shuttle as the substantially-depleted weft-bobbin is expelled, to prevent such old weft-end being drawn into the shed in the warps upon the next succeeding pick of the shuttle with the fresh supply of weft in the shuttle; and thus causing a double pick, which would injure the quality of the goods being woven. The said weft-parting is effected by a weft-parter mounted on the usual shuttle-feeler. When weaving with some classes of weft, as for instance coarse and heavy weft, or hard twisted and kinky weft, the portion of weft extending from the selvage-warps to the delivery eye of the shuttle frequently assumes positions which cause it to be missed by the said weft-parter. Consequently the duty of parting such portion is not performed.

One object of the invention is to provide means for holding and steadyng the weft-thread at a point between the selvage and the shuttle-box, to insure its entering the cutting jaws of the weft-parter and being severed each time such action is called for. Another object is to provide improved means for preventing the weft-thread from kinking at and adjacent the selvage-warps in the regular running of a loom.

The invention consists in a weft-holding brush or pad which is mounted upon the lay of a loom between the selvage-warps and the mouth of the adjacent shuttle-box, in position to engage the weft-thread between the selvage and the shuttle-box, and adapted to operate to hold it in position to be engaged by the weft-parting mechanism. Aside from its function in relation to the weft-parting mechanism the said brush or pad serves to prevent or reduce kinking of the weft.

An illustrative embodiment of the inven-

tion is shown in the accompanying drawings, in which,—

Fig. 1 is a view showing, partly in vertical section in a plane extending from front to rear in a loom, certain of the parts at the weft-replenishing end of the loom, with the device of the invention installed on the lay-beam.

Fig. 2 is a perspective view of certain of the parts of Fig. 1.

Fig. 3 is a perspective view of the brush or pad, shown separately.

Having reference to the drawings,—

A common means of effecting the necessary parting of the old weft which immediately precedes the expulsion of a substantially exhausted weft-carrier or bobbin from the shuttle of a loom is shown in Fig. 1. The parts shown are certain of the devices employed in effecting automatic weft-replenishment. In this familiar arrangement, a weft-parting device is mounted on the lower end of the shuttle-feeler 1, which latter swings rearward about pivot 2 when the parts are set to effect weft-replenishment by the action of the usual weft-detecting or feeling devices. The lower end of this shuttle-feeler moves rearward at this time to meet the advancing lay, crossing the lay-beam 3 in the groove 4 cut in the race-plate 19 just at the mouth of the shuttle-box, (not shown), to make sure that the shuttle 5 is fully entered within the shuttle-box and in position to receive the fresh weft-carrier. As this shuttle-feeling operation occurs, the weft-thread 6 stretching outward from the selvage-warps 7 to the delivery eye of the shuttle within the shuttle-box should enter the opening 8 between the cutting jaws of the weft-parter aforesaid, carried at the lower end of the shuttle-feeler 1, and be severed when the front of the lay-beam 3 strikes the tail 9 of the movable cutter-blade 10 to bring the said blade 10 down to sever the weft-thread.

As indicated hereinbefore, the portion of the weft-thread 6 extending between the selvage-warps and the shuttle-eye, is not always in proper position to enter between the cutting jaws. When this happens, the weft is not cut, and upon the next pick succeeding replenishment, with a full bobbin within the shuttle, the shuttle lays in the shed a pick of weft from the fresh weft-supply within the shed, and also trails into the shed the old weft-end which could not draw clear out of

the shuttle-eye because it had not been cut. This of course produces a defect in the cloth being woven, and makes trouble for the weaver, if he detects it in time to unweave the cloth and remove it. A number of double picks in a piece of cloth reduces the value of some kinds of cloth materially.

Referring now to my improved means for holding and steadyng the length of weft-threads 6 at a point between the selvage-warps 7 and the mouth of the shuttle-box:—

As already indicated, in carrying my invention into effect I mount a brush or pad upon the lay of the loom, between the selvage-warps 7 and the mouth of the shuttle-box at the side of the loom at which replenishment is effected. I employ a brush, substantially as shown, comprising bristles, hair, fibers, fine wire, or equivalent agencies, which are by nature adapted to hold lightly by frictional engagement a thread drawn across them. A practical embodiment of the idea is that shown in the drawings, namely a small brush-like device, Fig. 3, comprising a plurality of tufts 11, 11, set in a backing 12, and having a tang 13 combined with it, as by a screw 14, the device being mounted above the path of flight of the shuttle 5, with the bristles projecting down more or less into the path of the shuttle. The said device is conveniently affixed to the lay-cap 16 by a screw 18 occupying a vertical slot 15 in the said tang. The said slot permits the height of the device above the race-plate to be adjusted. The bristles are of a soft yielding nature, so as to be easily bent and deflected by the shuttle as it passes under them, without danger of deflecting the shuttle itself from its course, and extend down toward the race-plate sufficiently low to engage the portion of weft 6 which extends from the shuttle-eye and thread-groove 20 in the side of the shuttle inward to the selvage-warps. Thus the weft-thread 6, paid out from the flying shuttle at the height of said thread-groove 20, is engaged by the bristles as they spring back into their normal position following the passage of the shuttle under the brush. As the bristles engage the weft-thread almost at the rear end of the thread-groove 20 of the shuttle, and as this thread-groove is of course

always a fixed height above the race-plate 19, the weft-thread 6 is held at such height, and somewhat forward from the back of the shuttle-box, and consequently will enter the cutting jaws of the weft-parter with certainty to be parted thereby each time the shuttle-feeler is swung rearward in preparation for a renewal of the weft-supply.

What I claim as my invention is,—

1. In a loom in which replenishment is effected prior to complete exhaustion of the weft-supply within the working shuttle, the combination with the lay, and a shuttle-feeler having a weft-parter mounted upon it, of a weft-holder mounted above the path of the shuttle upon the lay between the selvage-warps and the shuttle-box at the side of the loom at which replenishment is effected and having bristles extending downward into the said path, in position with relation to the path of the shuttle to catch the weft-thread between the selvage of the cloth being woven and the shuttle-box mouth, to prevent the weft-thread from kinking in the regular working of the loom and to hold it in position for engagement by the said weft-parter.

2. In a weft-replenishing loom, the combination with the lay, a shuttle-box thereon, and a device which parts the old weft between the selvage-warps and a shuttle occupying the said shuttle-box, of a weft-detainer mounted upon the lay and extending from above the path of the shuttle downward into the said path between the selvage-warps and the shuttle-box mouth and under which the shuttle passes in its flight into such shuttle-box.

3. In a weft-replenishing loom, the combination with the lay, a shuttle-box thereon, and a device which parts the old weft between the selvage-warps and a shuttle occupying the said shuttle-box, of a weft-detainer mounted upon the lay and extending from above the path of the shuttle downward into the said path between the selvage-warps and the shuttle-box mouth and under which the shuttle passes in its flight into such shuttle-box, and means for vertically adjusting the working position of the said weft-detainer.
